UNITED STATES PATENT OFFICE.

GEORGE POMEROY, OF SAN FRANCISCO, CALIFORNIA, ASSIGNOR TO TRAVELERS' AID SOCIETY OF CALIFORNIA, OF SAN FRANCISCO, CALIFORNIA, A CORPORATION OF CALIFORNIA.

DESIGN FOR A BADGE.

46,967.

Specification for Design.

Patented Feb. 16, 1915.

Application filed November 23, 1914. Serial No. 873,652. Term of patent 14 years.

To all whom it may concern:

Be it known that I, GEORGE POMEROY, a citizen of the United States, residing in the city and county of San Francisco and State of California, have invented a new, original, and ornamental Design for Badges, of which the following is a specification, reference being had to the accompanying drawing, forming part thereof.

The figure is a front elevation of a badge illustrating my new design.

I claim:

The ornamental design for a badge, as shown.

GEORGE POMEROY.

Witnesses:

ARNOLD W. LIECHT,
EMILE J. HITTE.
